[57] CLAIM

The ornamental design for an orthodontic microbracket
with slot extension, as shown.

DESCRIPTION

FIG. 1 is a perspective view of the bracket;
FIG. 2 is a rear elevational view of the bracket of FIG.
1;

FIG. 3 is a bottom plan view of the bracket of FIG. 1;
FIG. 4 is a top plan view of the bracket of FIG. 1;
FIG. 5 is a front elevational view of the bracket of FIG.
1;

FIG. 6 is a right side elevational view of the bracket of
FIG. 1;

FIG. 7 is a left side elevational view of the bracket of
FIG. 1;

FIG. 8 is a perspective view of an alternative embodiment
of the bracket; and

FIG. 9 is a perspective view of another alternative
embodiment of the bracket.

DATED : April 14, 1987

INVENTOR(S) : Derek Evans

It is certified that error appears in the above-identified patent and that said Letters Patent is hereby corrected as shown below:

Fig. 12 is a front elevational view
of the embodiment of Fig. 8;

Fig. 13 is a left side elevational
view of the embodiment of Fig. 8;

Fig. 14 is a right side elevational
view of the embodiment of Fig. 8;

Fig. 15 is a perspective view of a
third embodiment thereof;

Fig. 16 is a rear elevational view
of the embodiment of Fig. 15;

Fig. 17 is a top plan view of the
embodiment of Fig. 15;

Fig. 18 is a bottom plan view of the
embodiment of Fig. 15;

Fig. 19 is a front elevational view
of the embodiment of Fig. 15;
